UNITED STATES PATENT OFFICE.

HENRY MARTIN, OF LANCASTER, AND GEORGE MARTIN, OF PHILADELPHIA,
PENNSYLVANIA.

BRICK-MOLD-SANDING MACHINE.

SPECIFICATION forming part of Letters Patent No. 359,267, dated March 15, 1887.

Application filed May 21, 1886. Serial No. 262,845. (No model.)

To all whom it may concern:

Be it known that we, HENRY MARTIN, residing at Lancaster city, in the county of Lancaster and State of Pennsylvania, and GEORGE 5 MARTIN, residing at Philadelphia, in the county of Philadelphia and State of Pennsylvania, both citizens of the United States, have invented certain new and useful Improvements 10 in Brick-Mold-Sanding Machines; and we do hereby declare the following to be a full, clear, and exact description of the invention, such as will enable others skilled in the art to which it appertains to make and use the same.

Our invention relates to that class of brick- 15 mold-sanding machines in which a rotating cylinder is used to contain the sand, with openings at various places on its periphery over which the molds are fastened, so that the action of revolving the cylinder will throw the sand from one set of molds into the other, and by this movement put them in proper condition 20 to receive the clay, at the same time economizing the use of the sand and preventing the same from getting on the outside of the 25 molds, which all brick-makers know saves the machine.

The object of our improvements are, first, the construction of a hexagonal cylinder in 30 which there are three open and three solid sides alternately, so that when the molds are fastened to the open sides there is always a solid side directly opposite; second, to construct a set of adjustable automatic lever-clamps to hold the molds fast onto the open 35 sides of the hexagonal cylinder; third, to construct a suitable roller-cam, and guide device to hold the levers in their proper position. We attain these objects by the mechanism illustrated in the following drawings, in which—

40 Figure 1 is a full perspective elevation of the machine. Fig. 2 is a full side sectional elevation, and Fig. 3 a full perspective end elevation of the same.

Similar letters refer to similar parts through 45 the several views.

Fig. 1: A represents a suitable frame to support this device; B, the mold in position on the cylinder, and C one of the flat sides of the same. D represents the cylinder itself; e, e, 50 the supports for the roller-cam; f, the guide

device for holding the lower levers in position; g' one of the lever-clamps, and h the spring which throws the clamp onto the mold when released by the cam.

In the sectional side elevation in Fig. 2, k 55 represents the bearings for the shaft; l, the shafts upon which the cylinder is keyed fast; i, the cams; m, the rollers upon which the cams act to throw the adjustable lever-clamps g' off the mold B when in the upper position, 60 as shown in Fig. 2, and o the adjustable part of the lever, which makes this clamp the required length to suit any thickness of molds.

In the end view, Fig. 3, the levers g and g' are shown. The two lower ones, g, are held 65 in place against the end of the cylinder, when in this position, by means of the guide-bar f, and the upper one, g', is thrown off of the molds by means of the cam i operating on the rollers m, which are journaled fast to the ends 70 of the lever-clamps g and g'.

Having thus described our invention, the manner of working it is as follows: The molds are placed on the open space of the sanding-machine, and the lever-clamps are adjusted to 75 suit their thickness by means of the bolt and loose jaw o. This jaw and lever both have oblong holes through them where the bolt goes in, so that they can be drawn in and out to suit the molds, as shown in Fig. 2. When this 80 is done, and the two molds are turned in the direction of the arrow to the positions a² and a³, Fig. 3, the machine is in position to receive the sand. It will be observed that by the box shape of the cylinder, directly under the mold 85 B, at a', is presented one of the flat sides of the cylinder. The object of this is to support the weight of the sand and not allow it to lie in the molds in the position that they are in at a² and a³, which is at rest, while the operator replaces the mold B a' with another, as it is a well-known fact that if the sand is allowed to lie in the molds for any time at rest 90 more than is required is sure to stick to the inside of them. As the molds are placed in 95 position at a', the operator, in drawing the machine toward him in the direction of the arrow, throws the roller m in on the end of the lever-clamp out of contact with cam i, thus allowing the spring h, Fig. 2, to throw the adjusted 100

lever-clamp onto the end of the mold on both ends at the same time and hold it rigidly in position. At one-twelfth of the revolution the end of this lever-clamp comes in contact with the guide-bar *f*, which holds it firmly on the molds, as at *a*², Fig. 3. This bar continues to hold it in position until it is past the point occupied by the mold *a*³. It then releases the lever-clamp just before the roller *m* comes in contact with the point of the cam *i*. It is this part of the cam which drives the roller down and compresses the spring *h*, and throws the lever-clamps in the position that is shown at *g*', Fig. 2, thus releasing the mold *B*, which is then removed and replaced by another, and so the operator continues.

The machine being entirely automatic in its action, it is only necessary for the operator to take one mold off, put another on, and turn the machine either to the right or left, so as to bring one of the already sanded molds on top in position to be changed for another, and as the cylinder constructed in this manner is at all times balanced by the weight of the molds, a boy can easily work it instead of a man, and it can be run by power, if so desired.

We are aware that prior to our invention cylinders have been made for this purpose.

Therefore we do not claim the cylinders, broadly; but

What we do claim as our invention, and desire to secure by Letters Patent, is—

1. In combination with the cylinder and pivoted lever-clamps for holding the molds in place, the springs *h*, which act against said lever-clamps to cause this holding action, substantially as set forth.

2. The lever-clamps *g*', provided with extensible plates *o*, making said lever-clamps adjustable, in combination with a brick-holding cylinder, substantially as set forth.

3. A brick-holding cylinder, in combination with lever-clamps for holding the brick-molds, guide-bar *f*, which holds said clamp against said molds during a part of the revolution, and the independent cams *a*', arranged to withdraw said lever-clamps from said molds, substantially as set forth.

In testimony whereof we affix our signatures in presence of two witnesses.

HENRY MARTIN.
GEORGE MARTIN.
